UNITED STATES PATENT OFFICE

1,988,467
TIME FUSE FOR PROJECTILES
Samuel Wiley, Metuchen, N. J.
Application March 10, 1934, Serial No. 714,940
10 Claims. (Cl. 102—36)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a time fuse for projectiles.

In the powder time fuse which has been used for many years the powder train is packed in grooves or channels and during combustion the residue of the powder frequently obstructs the vents in the fuse casing and affects the rate of burning. The powder time train is also readily affected by moisture.

10 The purpose of this invention is to provide a powder time fuse in which the powder train is placed in a metallic tubular casing which is cut upon actuation of the firing mechanism provided for igniting the powder train.

15 A further object of the invention is to so organize these elements that the fuse may be set and reset at will.

20 As an additional precaution against moisture the fuse casing is sealed until used when the fuse cutter provides a vent.

25 With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

30 A practical embodiment of the invention is illustrated in the accompanying drawing, where-
in:

35 Fig. 1 is a horizontal sectional view of the im-
proved fuse taken on the line 1—1 of Fig. 2.

40 Fig. 2 is a longitudinal sectional view on the
line 2—2 of Fig. 1.

45 Fig. 3 is a fragmentary longitudinal sectional
view on the line 3—3 of Fig. 1.

Fig. 4 is a view in side elevation showing the
time scale.

50 The fuse consists generally of a base 5, a head 6, and a rotatably mounted ring 7 interposed be-
tween a portion of the base and head. The base is formed with a tubular stem 8 having threads 9 providing for attachment of the head 6. A
plunger 10 mounted in the usual manner in the
mouth of the stem by the ring 11 carries a primer
charge 12 adapted to be set off by a firing pin 13.

55 The forward face of the base, constituting the
seat for the ring 7, is formed with an annular
channel 15 for partially receiving a metal tube

16, such as lead, in which is carried a powder
time train 17. The ends of the tube 16 are in-
serted in recesses 18 and 19 in a block 20 which
is fixed to the base 5. The recess 18 is blind
while the recess 19 is in communication with an
inclined passage 21 in the base. The passage
21 contains a powder pellet 22 and leads to the
booster charge 23 in the rear end of the base.
The block is also provided with an aperture 24
positioned between the recesses 18 and 19.

5 The ring 7 is formed with an annular channel
25 complementary to but of greater diameter
than the channel 15 in the base and partially re-
ceives the tube 16. A radially disposed passage
26 in the ring 7 intersects the channel 25 and is
closed at its outer end by a cover 27. A plunger
28 normally carried in the inner part of the
passage 26 is adapted on being moved to cut the
tube 16 and cover 27.

10 The tubular stem 8 of the base is formed with
a series of radial ports 29 leading to an annular
groove 30 which is disposed in the plane of the
plunger 28.

15 The position of the plunger 28 relative to the
recess 19 is indicated in the usual manner em-
ployed in time fuses by means of a mark 31 and
scale 32 inscribed respectively on the rotatable
ring 7 and on the base 5. The plunger is in the
safe position when it is positioned in line with
the aperture 24 in the block 20 so that in the
event of accidental operation the plunger will be
20 driven out of the fuse without cutting the time
train.

25 When a projectile equipped with the fuse is
fired from a gun, the plunger 10 sets back and
the primer charge 12 is fired by the pin 13. The
gases from the exploded primer charge 12 create
sufficient pressure to drive the plunger 28 through
the tube 16 and cover 27 and entirely out of the
ring 7. The flame from the primer ignites the
30 powder time train 17 which burns towards each
of its ends, but can only transmit ignition from
the end in the open recess 19.

35 The gases from the burning powder train are
vented through the opening made in the cover 27
40 by the plunger 28. The channel 25 in the ring
7 is of greater diameter than the tube 16 and pro-
vides ample venting space to insure free and uni-
form combustion of the time train 17.

45 This construction provides a fuse which is
moisture-proof until fired and which can be set
and re-set at will. The rate of burning of the
powder time train will always be uniform.

I claim.

50 1. In a time fuse, a base formed with an an-

nular chamber, a tubular stem on the base having ports, a firing mechanism carried by the stem, an encased powder time train partially disposed in the channel of the base, a block in the base 5 having recesses receiving the ends of the powder train, one of said recesses being blind and the other being open, said block having an aperture positioned between the ends of the powder train, a ring rotatably mounted on the base and having 10 a channel complementary to the channel in the base but of greater diameter than the powder train, said ring also having a radial passage intersecting the channel and in the plane of the ports of the stem and the aperture in the block, 15 a cover closing the outer end of the passage in the ring, and a cutter for the time train normally positioned in the inner end of said passage.

2. In a time fuse, a base formed with an annular chamber, a tubular stem on the base having ports, a firing mechanism carried by the stem, an encased powder time train partially disposed in the channel of the base, a block in the base having recesses receiving the ends of the powder train, one of said recesses being blind 20 and the other being open, a ring rotatably mounted on the base and having a channel complementary to the channel in the base but of greater diameter than the powder train, said ring also having a radial passage intersecting the channel and in the plane of the ports of the stem, a cover closing the outer end of the passage in the ring, and a cutter for the time train normally positioned in the inner end of said passage.

3. In a time fuse, a base formed with an annular chamber, a tubular stem on the base having ports, a firing mechanism carried by the stem, an encased powder time train partially disposed in the channel of the base and having a blind end and an open end, a ring rotatably 25 mounted on the base and having a channel complementary to the channel in the base but of greater diameter than the powder train, said ring also having a radial passage intersecting the channel and in the plane of the ports of the stem, a cover closing the outer end of the passage in the ring, and a cutter for the time train normally positioned in the inner end of said passage.

4. In a time fuse, a base formed with an annular chamber, a tubular stem on the base having ports, a firing mechanism carried by the stem, an encased powder time train partially disposed in the channel of the base and having a blind end and an open end, a ring rotatably mounted on the base and having a channel complementary to the 30 channel in the base, said ring also having a radial passage intersecting the channel and in the plane of the ports of the stem, a cover closing the outer end of the passage, and a cutter for the time train normally positioned in the inner end of said passage.

5. In a time fuse, a base formed with an annular channel, a tubular stem on the base having

ports, a firing mechanism carried by the stem, an encased powder time train partially disposed in the channel of the base and having a blind end and an open end, a ring rotatably mounted on the base and having a channel complementary to the channel in the base, said ring also having a radial passage intersecting the channel and in communication with the ports of the stem, a cover closing the outer end of the passage, and a cutter for the time train normally positioned in the inner end of said passage.

6. In a time fuse, a base formed with an annular channel, a tubular stem on the base having ports, a firing mechanism carried by the stem, an encased powder time train partially disposed in the channel of the base and having a blind end and an open end, a ring rotatably mounted on the base and having a channel complementary to the channel in the base, said ring also having a radial passage intersecting the channel and in communication with the ports of the stem, and a cutter for the time train normally positioned in the inner end of said passage.

7. In a time fuse, a base, an enclosed powder time train carried by the base and projecting above the surface of the base, a ring rotatably mounted on the base and having a channel receiving the projecting part of the time train, said ring also having a passage intersecting the channel, a cover closing the outer end of the passage, a cutter for the time train normally positioned in the inner end of said passage, and a firing mechanism carried by the base for driving the cutter through the time train and closure and for igniting the time train.

8. In a time fuse, a base, an enclosed powder time train carried by the base and projecting above the surface of the base, a ring rotatably mounted on the base and having a channel receiving the projecting part of the time train, said ring also having a passage intersecting the channel, a cutter for the time train normally positioned in the inner end of said passage, and a firing mechanism carried by the base for driving the cutter through the time train and for igniting the time train.

9. In a time fuse, a base, an encased powder time train carried by the base, a ring rotatably mounted on the base and having a passage, a cover closing the outer end of the passage, a cutter for the time train normally positioned in the inner end of said passage, and a firing mechanism carried by the base for driving the cutter through the time train and closure and for igniting the time train.

10. In a time fuse, a casing, a powder time train in the casing, means for igniting the time train, and means adapted to be driven through the wall of the casing by said preceding means to vent the casing.

SAMUEL WILEY.
